UNITED STATES PATENT OFFICE.

GEORGE PURVIS, OF PORT HURON, MICHIGAN.

BLOW-OFF FOR BOILERS.

1,351,586.

Specification of Letters Patent. Patented Aug. 31, 1920.

Application filed June 7, 1918. Serial No. 238,799.

To all whom it may concern:

Be it known that I, GEORGE PURVIS, a citizen of the United States of America, residing at Port Huron, in the county of St.

5 Clair and State of Michigan, have invented certain new and useful Improvements in Blow-Offs for Boilers, of which the following is a specification, reference being had to the accompanying drawings.

10 This invention relates to a blow off device for boilers and particularly an arrangement thereof whereby it may be readily inserted in a place provided for the hand hole plate of a boiler, especially one of the marine 15 type, or a similar aperture, the device being operable from the exterior of the boiler.

The invention consists in the matters hereinafter set forth, and more particularly pointed out in the appended claims.

20 In the drawings,

Figure 1 is a view in longitudinal section, partially broken away and in elevation, of a boiler equipped with a device that embodies features of the invention;

25 Fig. 2 is a view in end elevation of the lower portion of the boiler;

Fig. 3 is a view in detail of a distributor taken in longitudinal section;

30 Fig. 4 is a view in section on or above line IV—IV of Fig. 3;

Fig. 5 is a view in detail of the exterior casing of the distributor; and

Fig. 6 is a view in detail of an indicator plate.

35 As herein shown in preferred form, a cylindrical casing 1 is secured at the outer end in an aperture of a boiler head 2 by studs 3 or the like which pass through an annular flange 4 of a blow off fitting 5. A

40 plurality of conductor pipes 6 extend from nipples 7 in the casing 1 to the lower portion of the boiler shell 8 where they terminate in appropriately formed collecting nozzles 9 which are so disposed as to readily

45 indraw sediment and the like from the adjacent portions of the shell and deliver it to the conductors. An inlet pipe 10 from an appropriately positioned nipple on the casing extends to the steam space above the

50 normal water level of the boiler where it may terminate in a grease pan 11 of suitable design.

A valve closure in the form of a sleeve 12 is rotatable in the casing 1 by means of a stem 13 which passes through a suitable packing gland 14 of the nipple 5, and which

has a squared or splined portion 15 in non-rotatable and longitudinally reciprocable engagement with a bridge 16 across the sleeve. The distance between the bridge 16 and an annular valve seat 17 on the inner end portion of the nipple 5 is such as to allow the stem, because of its engagement by coarse screw threads 18 which cause it to move longitudinally when rotated by a hand wheel 19, to shift enough so that a valve closure 20 recedes from the valve seat 17 before any one of a series of apertures 21 comes in to register with any one of the nipples 7.

70 The nipples 7 are so disposed in regular order around and along the casing that the apertures on the ports 21 may be brought successively in to register with those nipples, an index finger 22 on the stem, which traverses a suitable dial indicator 23, advising the operator of the action and position of the distributor.

One great advantage of this arrangement is its particular adaptability for boilers of 80 the marine type such as indicated, in the drawings, as it can be readily secured in position after the proper fitting of the various pipes without the necessity of alining the parts inside of the boiler, and the securing it in places which are not easy of access, as the distributing valve and operating parts are a rigid unitary structure when once secured in position, and there is no possibility of their getting out of alinement, 85 and consequently the device is always operable.

Obviously, changes in the detail of construction may be made without departing from the spirit of the invention and I do 95 not limit myself to any particular form and arrangement of parts.

What I claim is:—

1. A blow-off for boilers comprising a selective valve having a plurality of distributed nozzles and an outlet having its axis alined with the valve axis, a controllable closure for the outlet and positioned to be located within the boiler when the blow-off is in position, and means for controlling 100 the movements of the valve and closure, said means being positioned to be accessible externally of the boiler when the blow-off is installed.

2. A blow-off of the type of claim 1 characterized in that the valve casing and outlet member are separable to permit location on 110

opposite sides of a boiler wall, the casing and member being relatively formed to locate a member portion within the casing, the securing means for connecting the member and casing together extending through the boiler wall.

3. A blow-off of the type of claim 1 characterized in that the closure for the outlet is movable in the direction of the selective 10 valve axis.

4. A blow-off of the type of claim 1 characterized in that the closure for the outlet is formed with a threaded stem, rotating movement of the stem moving the closure in the 15 direction of the selective valve axis.

5. A blow-off for boilers comprising a selective valve having a plurality of distributed nozzles and an outlet having its axis alined with the valve axis, a controllable closure for the outlet, said closure being movable in the direction of the valve axis and being operatively connected to the valve to rotate the latter on its axis during closure movement.

25 6. A blow-off of the type of claim 5 characterized in that the connections of closure and valve are arranged in a manner whereby activity of either of the valve nozzles is dependent upon advance movement of the 30 closure from its seat.

7. A blow-off of the type of claim 5 characterized in that the closure is movable rotatively by an element exposed without the boiler, the blow-off structure having visual 35 indication means to permit proper control movements of the element, said means including an indicator carried by and movable with the element.

8. The combination with an end wall of a 40 boiler having an opening, of a blow-off unit

positionable on said wall to locate a portion interior of the boiler and the remainder exterior of such boiler, said unit including a casing supported on the inner side of the wall and having connection with a plurality 45 of collective nozzles, a selective valve controlling the activity of the nozzles, an outlet leading to and axially alined with the valve, and exposed exterior of such wall, and an element operative to control said outlet and the movement of said valve.

9. The combination with a boiler having a curved lower wall, and an end wall having an opening spaced from a vertical plane extending through the radial center of the 55 lower wall, of a blow-off device including a valve casing secured to said end wall and projecting into the boiler space a distance less than that of the boiler length, a plurality of collection nozzles located adjacent such 60 vertical plane at spaced points in the direction of boiler length, individual connections between the casing and each nozzle, and means for controlling said connections, said means including a rotatable element within 65 the casing, and an element manipulating unit projecting through said opening, said unit including a closure and seat adapted to control the outlet of the casing.

10. Apparatus as in claim 9 characterized 70 in that the closure and rotatable element are operatively connected to rotate in unison and to permit relative movement in the direction of element axis.

In testimony whereof I affix my signature 75 in presence of two witnesses.

GEORGE PURVIS.
